UNITED STATES PATENT OFFICE

2,672,791

CONTAINER CLOSING MACHINE WITH
CENTERING DEVICE

Howard B. Peterson and Edward De Gear, San Francisco, Calif., assignors to American Can Company, New York, N. Y., a corporation of New Jersey

Application March 28, 1952, Serial No. 279,114

7 Claims. (Cl. 93—39.2)

1 The present invention relates to a can or container closing machine and has particular reference to movable centering devices for centering and laterally supporting fibre or similar containers or container bodies received on the lifter pads of the machine preparatory to attaching covers or end members to the containers or the bodies.

An object of the invention is the provision in a container closing machine of movable centering devices which are associated with the lifter pads of the machine and which are movable into a guiding position above the container supporting face of the pads to engage against, center, and support the lower end of a container received on a pad for elevation into closing position in the machine.

Another object is the provision of such centering devices wherein the devices have arcuate movements in a vertical direction adjacent the lifter pads so that they disappear below the top or container supporting face of the pads to prevent interference with the feeding of containers or bodies onto the pads.

Another object is the provision of such centering devices wherein the devices are actuated into and out of centering position relative to the top face of the lifter pads through movement of the pads into and out of container closing position.

Another object is the provision of such centering devices wherein the devices move into operative position while a lifter pad is elevating a container or a body into closing position, the devices moving in toward the container or body as the latter rises, thereby effecting a gentle centralizing of the container or body on the lifter pad and imparting a final setting or firm supporting of the container or body just as the lifter pad reaches the peak of its stroke to properly locate and hold the lower end of the container or body firm during the closing operation.

Numerous other objects and advantages of the invention will be apparent as it is better understood from the following description, which, taken in connection with the accompanying drawings, discloses a preferred embodiment thereof.

Referring to the drawings:

Figure 1 is a vertical section taken through a container closing machine embodying the instant invention, with parts broken away;

Fig. 2 is a plan view of the container entrance portion of the machine as taken substantially along a horizontal plane indicated by the line 2—2 in Fig. 1, with parts broken away;

Fig. 3 is an enlarged sectional view of the

centering devices, the view being taken substantially along the line 3—3 in Fig. 2;

Fig. 4 is an exploded perspective view of the parts embodied in the centering devices;

Figs. 5 and 6 are enlarged elevations of the lifter pads and their associated centering devices, the two views showing different positions of the parts involved; and

Fig. 7 is an enlarged elevation of the opposite side of the devices shown in Figs. 5 and 6, the view showing one position of the centering device in full lines and another position in dotted lines.

As a preferred or exemplary embodiment of the instant invention the drawings illustrate principal parts of a can or container closing machine of the character disclosed in Figs. 3 of United States Patent 2,039,338 issued May 5, 1936, to R. E. J. Nordquist on Vacuum Closing Machine and United States Patent 2,447,525 issued August 24, 1948, to R. E. J. Nordquist on Can Closing Machine.

The machine illustrated in the drawings is designed to attach metal rectangular end members to fibre rectangular container bodies A (Figs. 1 and 2) to produce containers commonly used for frozen food products, cocoa, etc., although the invention is equally well adapted to containers, container bodies and end members of other shapes and materials.

In such a closing machine, the fibre container bodies A are received from any suitable source of supply in an upright position, standing on one end, and are fed into the machine in processional order along a horizontal runway 11 (Fig. 2) formed in a table 12 (see also Fig. 1) supported on a base 13 which comprises a part of the main frame of the machine. A pair of spaced and parallel guide rails 15, 16 disposed adjacent the runway 11 maintain the bodies A in processional order.

The bodies A are advanced along the runway 11 in spaced and timed relation by an endless double chain conveyor 18 (Figs. 1 and 2) having feed dogs 19 which project laterally from the conveyor into the runway and engage behind the bodies A therein. The conveyor 18 is disposed parallel with the runway 11 and its upper run rides upon a track 21 embedded in the table 12. The conveyor operates over pairs of sprockets 23 carried on a drive shaft 24 journaled in a bearing formed in the table. The shaft 24 is driven continuously in any suitable manner such as that disclosed in the Nordquist Patent 2,447,525 mentioned above.

The container bodies A advanced along the

runway 11 are directed toward a rotating horizontal turret 27 having a hub 28 (Fig. 1) mounted on a stationary vertical shaft 29 secured in the frame of the machine. The turret is rotated continuously in time with the conveyor 18 by way of a gear 31 which is keyed to the lower end of the hub 28.

The turret 27, adjacent its outer periphery carries a plurality of lifter devices 32 (Fig. 1) of the character disclosed in Fig. 3 of the Nordquist Patent 2,039,338 above mentioned. These lifter devices 32 comprise vertically movable stems 33 which slide in bearing blocks 34 secured to the turret. A dust cap 35 is secured to the top of the stem and extends down around the outside of the bearing block. The dust cap supports a rectangular shaped lifter pad 36 which projects up from the cap and which terminates in a flat top face 37 which is in a horizontal plane flush with the runway 11 when the lifter pad moves past the runway so as to receive and support a container body A from the runway as will be hereinafter more fully explained.

The lower end of each of the lifter stems 33 carries a pair of cam rollers 38, 39 which operate against a pair of co-operating stationary cam tracks 41, 42 formed in the base 13 and surrounding the stationary shaft 29 so that as the turret rotates around the shaft 29, the cam rollers traverse the cam tracks and thus raise and lower the lifter devices in time with the operation of the machine, as in the Nordquist Patent 2,039,338.

Above each lifter device 32, the upper end of the turret hub 28 carries an end member supporting ring 45 which receives a container end member in any suitable manner for attachment to a container body A. Each ring is spaced just below a conventional closing head 46 for receiving the end member and the upper end of the container body A to unite them in a suitable seam. There is one closing head for each lifter device 32 and they are carried on an auxiliary device 47 resting on and rotating with the turret hub 28 around the stationary shaft 29. The heads shown in the drawings are commonly known as die seamer heads as contradistinguished from the roller type closing head shown in the Nordquist patents above mentioned.

Hence as the turret 27 rotates, it carries each of the lifter devices 32 in succession past the terminal end of the runway 11 and momentarily positions its lifter pad 36 in direct alignment with the runway 11 as best shown in Fig. 2. While the lifter pad 36 is passing into and out of this alignment, without stopping, the conveyor 18 by way of one of its feed dogs 19 advances a container body A from the runway onto the lifter pad. Continued rotation of the turret 27 carries the lifter pad 36 with its container body A through a curved path of travel away from the runway. During this travel of the turret 27, the cam tracks 41, 42 raise the lifter pad 36 and its container body A so that the upper end of the body will pick up the end closure member in the support ring 45 and carry it up into the closing head 46 for attachment to the body as mentioned hereinbefore.

In order to properly locate the container body A in a center position on the flat top face 37 of the lifter pad 36 when the body is received from the runway 11, each lifter pad 36 is provided with a pair of oscillatable centering and support fingers 51 (Figs. 3, 4, 6 and 7). The lifter pad 36 is rectangular in shape to correspond substantially to the rectangular shape of the container 75 pad 36.

body A and is slightly larger than the body, and there are two of the centering fingers 51 for each lifter pad, one disposed along each longitudinal side of the lifter pad. The sides and ends of the lifter pad are vertical and straight.

Each centering finger 51 is a wide bell crank shaped member having a continuous upper centering edge 52 which extends along the full length of the longitudinal sides of the lifter pad 36. The lower edge of each finger is rounded and forms a slide edge 53. This edge, at the middle of the finger is cut away to provide a clearance recess 54 for the outer end of a rocker arm 55. There are two rocker arms 55 for each lifter pad 36 and their outer ends are pivotally connected to the fingers 51 by pivot pins 56. The inner ends of the two rocker arms 55 extend into a recess 57 in the lifter pad 36 and are mounted on pivot pins 58 which extend through the lifter pad and the recess.

Adjacent one end of the lifter pad 36, the slide edges 53 of the two fingers 51 are secured to the outer ends of a pair of short tension springs 59 (Fig. 7). The inner ends of the springs 59 are secured to a pin 61 secured in the lifter pad 36 adjacent its lower edge and near its center. These springs 59 keep the slide edges 53 of the fingers in frictional engagement with the outer longitudinal vertical faces of the lifter pad as best shown in Fig. 7.

Adjacent the opposite end of the lifter pad 36, the rocker arm pivot pins 58 extend beyond the lifter pad and carry a pair of meshing spur gears 62 (Figs. 5 and 6) to provide oscillation of the rocker arms 55 in unison to move the centering fingers 51 through an arc terminating below and above the container supporting face 37 of the lifter pad 36. One of the pivot pins 58 is longer than the other and also carries an actuating lever 63 which is keyed to the pin. The outer end of this actuating lever 63 is pivotally connected to the upper end of a link 64 which at its lower end is pivotally connected to a stationary block 65 bolted to the turret 27. Thus the lower end of the link is fixed while the upper end is movable, with the result that the link can swing on its fixed lower end.

The normal positions of the centering finger members are shown in Fig. 5 in which the lifter pad 36 is at its lowermost level with its top face 37 flush with the runway 11 and with the centering fingers 51 in a depressed or lowered position adjacent the sides of the lifter pad 36 and well below the top face 37 of the pad. The parts are in these positions when the lifter pad 36 passes the terminal end of the runway 11 and receives a container body A therefrom without in anyway interfering with the centering fingers 51, Figure 5 showing the newly received body in a slightly off-center relation to the lifter pad.

As soon as the lifter pad 36 passes beyond the runway 11 it starts its upward travel to lift the body into position in the closing head 46. With this rise of the lifter pad, the inner end of the actuating lever 63 rises with the pad while its outer end, connected to the link 64 tends to remain stationary. This action rotates the pivot pin 58 connected to the actuating lever 63 and thus through the gears 62 which are at all times in mesh, rotates both pivot pins 58 in opposite directions. The rotation of the pivot pins 58 swing the rocker arms 55 upwardly in unison and thus cause the centering fingers 51 to swing upwardly through an arc toward the top 37 of the lifter pad 36.

Since the lower or slide edges 53 of the centering fingers are kept in engagement with the vertical sides of the lifter pad 36, they move upwardly in a straight line and this causes the upper or centering edges 52 of the fingers to swing through an arc which first carries them away from the lifter pad and second, swings them inwardly over the top face 37 of the lifter pad 36 and hence toward each other, gently engaging the longitudinal sides of the body A and pushing the body A from the off-set position shown in Fig. 5 into a centralized position on the lifter pad, as shown in Fig. 6.

This centralizing of the body A on the lifter pad 36 takes place just before the top end of the body reaches the end member support ring 45 so that the body is substantially located before it enters the ring as mentioned hereinbefore. During the remaining short distance the body A is raised, the upper end passing through the closure support ring 45, picking up the closure and presenting the top portion of the body with the closure to the closing head 46. The lifter pad 36 continues to rise and the centering fingers 51 continue to press against the body and thereby firmly support it during the closing operation. This inward travel however is slight and gentle because of the angular position of the actuating lever 63 relative to the link 64 as will be seen by reference to Fig. 6.

With such an arrangement of links and levers a simple, gentle, harmonic motion is set up in the rocker arms 55 and the centering fingers 51 which provides for a rapid rise of the fingers as the actuating lever 63 moves from its substantially horizontal position as shown in Fig. 5. As the actuating lever 63 approaches its more vertical position as shown in Fig. 6 its turning effect on the rocker arms 55 is considerably slower and hence the inward travel of the fingers toward each other is correspondingly slower. It is for this reason that the final firm support of the body A is effected at substantially the end of the up stroke of the lifter pad and in a gentle manner.

After the closing operation takes place, the lifter pad 36 descends to its original position and accordingly the centering fingers move down below the top of the lifter pad to their original position adjacent its vertical side faces, and thus permit the discharge of the closed body and the reception of a new unclosed body without in any way interfering with the transfer of the body from and to the lifter pad.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

We claim:

1. In a machine for attaching end members to tubular container bodies, the combination of a vertically movable lifter pad having a supporting face for receiving and supporting a container body for the attachment of an end member thereto, means for raising and lowering said lifter pad, means for feeding a container body to said container supporting face of the lifter pad when the latter is in lowered position, means for attaching an end member to said container body when said lifter pad is in raised position, means for discharging the container with an end mem-

ber thus attached from said lifter pad when the latter is again lowered, a pair of centering fingers pivotally mounted on said lifter pad on opposite sides thereof and movable vertically through an arc terminating below and above the container supporting face of said lifter pad and actuating means for swinging said fingers into a position below the supporting face of said lifter pad to free said face of interference by said fingers when a container body is received on said face from said feeding means and when it is removed therefrom by said discharging means and for swinging said fingers into a position above and overlapping the supporting face of said lifter pad to engage and centralize said container on said face while the lifter pad is being raised.

2. In a machine for attaching end members to tubular container bodies, the combination of a vertically movable lifter pad having a supporting face for receiving and supporting a container body for the attachment of an end member thereto, means for raising and lowering said lifter pad, means for feeding a container body to said container supporting face of the lifter pad when the latter is in lowered position, means for attaching an end member to said container body when said lifter pad is in raised position, means for discharging the container with an end member thus attached from said lifter pad when the latter is again lowered, a pair of centering fingers pivotally mounted on said lifter pad on opposite sides thereof and movable vertically through an arc terminating below and above the container supporting face of said lifter pad, means connecting said fingers for swinging them in unison, and actuating means for swinging said fingers into a position below the supporting face of said lifter pad to free said face of interference by said fingers when a container body is received on said face from said feeding means and when it is removed therefrom by said discharging means and for swinging said fingers into a position above and overlapping the supporting face of said lifter pad to engage and centralize said container on said face while the lifter pad is being raised.

3. In a machine for attaching end members to tubular container bodies, the combination of a vertically movable lifter pad having a supporting face for receiving and supporting a container body for the attachment of an end member thereto, means for raising and lowering said lifter pad, means for feeding a container body to said container supporting face of the lifter pad when the latter is in lowered position, means for attaching an end member to said container body when said lifter pad is in raised position, means for discharging the container with an end member thus attached from said lifter pad when the latter is again lowered, a pair of rocker arms pivotally mounted on said lifter pad on opposite sides thereof and movable vertically through an arc terminating below and above the container supporting face of said lifter pad, a centering finger mounted on each of said rocker arms and movable with said arms through said arc, and actuating means for swinging said fingers into a position below the supporting face of said lifter pad to free said face of interference by said fingers when a container body is received on said face from said feeding means and when it is removed therefrom by said discharging means and for swinging said fingers into a position above and overlapping the supporting

face of said lifter pad to engage and centralize said container on said face while the lifter pad is being raised.

4. In a machine for attaching end members to tubular container bodies, the combination of a vertically movable lifter pad having a supporting face for receiving and supporting a container body for the attachment of an end member thereto, means for raising and lowering said lifter pad, means for feeding a container body to said container supporting face of the lifter pad when the latter is in lowered position, means for attaching an end member to said container body when said lifter pad is in raised position, means for discharging the container with an end member thus attached from said lifter pad when the latter is again lowered, a pair of pivot pins mounted in said lifter pad, a pair of rocker arms mounted one on each of said pivot pins and extending in opposite directions beyond said lifter pad and movable vertically through an arc terminating below and above the container supporting face of said lifter pad, a centering finger mounted on each of said rocker arms and movable with said arms through said arc, a pair of meshing gears mounted on said pivot pins for swinging said rocker arms and the fingers carried thereon in unison, and actuating means for swinging said fingers into a position below the supporting face of said lifter pad to free said face of interference by said fingers when a container body is received on said face from said feeding means and when it is removed therefrom by said discharging means and for swinging said fingers into a position above and overlapping the supporting face of said lifter pad to engage and centralize said container on said face while the lifter pad is being raised.

5. In a machine for attaching end members to tubular container bodies, the combination of a vertically movable lifter pad having a supporting face for receiving and supporting a container body for the attachment of an end member thereto, means for raising and lowering said lifter pad, means for feeding a container body to said container supporting face of the lifter pad when the latter is in lowered position, means for attaching an end member to said container body when said lifter pad is in raised position, means for discharging the container with an end member thus attached from said lifter pad when the latter is again lowered, a pair of rocker arms pivotally mounted on said lifter pad on opposite sides thereof and movable vertically through an arc terminating below and above the container supporting face of said lifter pad, a centering finger pivotally mounted on each of said rocker arms and movable with said arms through said arc, said centering fingers having an upper centering edge and a lower slide edge, pressure means operable against said fingers for maintaining said slide edges in sliding engagement with the sides of said lifter pad for controlling the arcuate movement of the centering edges of said fingers, and actuating means for swinging the centering edge of said fingers into a position below the supporting face of said lifter pad to free said face of interference by said fingers when a container body is received on said face from said feeding means and when it is removed therefrom by said discharging means and for swinging the centering edge of said fingers into a position above and overlapping the supporting face of said lifter pad to engage and centralize said container on said face while the lifter pad is being raised.

said container on said face while the lifter pad is being raised.

6. In a machine for attaching end members to tubular container bodies, the combination of a vertically movable lifter pad having a supporting face for receiving and supporting a container body for the attachment of an end member thereto, means for raising and lowering said lifter pad, means for feeding a container body to said container supporting face of the lifter pad when the latter is in lowered position, means for attaching an end member to said container body when said lifter pad is in raised position, means for discharging the container with an end member thus attached from said lifter pad when the latter is again lowered, a pair of centering fingers pivotally mounted on said lifter pad on opposite sides thereof and movable vertically through an arc terminating below and above the container supporting face of said lifter pad, an actuating arm for moving said fingers through said arc, and a link pivotally connected at one end to said actuating arm and at its opposite end to a fixed member whereby the lowering of said lifter pad swings said fingers into a position below the supporting face of said lifter pad to free said face of interference by said fingers when a container body is received on said face from said feeding means and when it is removed therefrom by said discharging means and the raising of said lifter pad swings said fingers into a position above and overlapping the supporting face of said lifter pad to engage and centralize said container on said face while the lifter pad is being raised.

7. In a machine for attaching end members to tubular container bodies, the combination of a vertically movable lifter pad having a supporting face for receiving and supporting a container body for the attachment of an end member thereto, means for raising and lowering said lifter pad, feeding means disposed at a level with the supporting face of said lifter pad when in its lowered position for advancing said container body into position onto said face, closing means disposed remotely from said feeding means for receiving and attaching an end member to said body when said lifter pad is in its raised position, means for discharging the container with a thus attached end member from said lifter pad when the latter is again lowered, a pair of centering fingers pivotally mounted on said lifter pad on opposite sides thereof and movable through an arc terminating below and above the container supporting face of said lifter pad, and actuating means for swinging said fingers into a position below the supporting face of said lifter pad to free said face of interference by said fingers when a container body is received on said face from said feeding means and when it is removed therefrom by said discharging means and for swinging said fingers into a position above and overlapping the supporting face of said lifter pad to engage and centralize said container on said face while the lifter pad is being raised.

HOWARD B. PETERSON.
